UNITED STATES PATENT OFFICE.

EDWARD PERRIN, OF KIDDERMINSTER, COUNTY OF WORCESTER, ENGLAND, ASSIGNOR TO HORNER BROTHERS, OF PHILADELPHIA, PA.

DESIGN FOR A CARPET.

SPECIFICATION forming part of Design No. 12,852, dated April 4, 1882.

Application filed March 2, 1882. Term of patent 3½ years.

To all whom it may concern:

Be it known that I, EDWARD PERRIN, of Kidderminster, Worcestershire, England, have invented and produced a new and original 5 Design for Carpets, of which the following is a specification.

The nature of my design is fully represented in the accompanying photographic illustration, to which reference is made.

I claim as my invention—

The design for a carpet, as shown.

Witnesses: EDWD. PERRIN.

JAMES GREENWOOD,

THOMAS GRIFFIN.
